UNITED STATES PATENT OFFICE

IRVING E. ASKE, OF DULUTH, MINNESOTA

HYDROCARBON-FEEDING SYSTEM FOR VAPORIZING DEVICES

Application filed January 5, 1926. Serial No. 79,337.

My invention relates to devices for automatically feeding hydrocarbon to a vaporizing device, and has for its object the provision of novel and simple means whereby a portion 5 of liquid hydrocarbon, or wet hydrocarbon vapor, for combustion in the cylinder of an internal explosion engine may, on its way to such cylinder, be automatically and positively conducted to a pre-heating vaporizer 10 adapted to transform it into heated fumes. Another object is to provide a simple and efficient device of the character indicated comprising a novel form of horizontal type carburetor. With these and other objects in 15 view, it consists of the constructions, combinations and arrangements of parts herein-after described and claimed.

In the accompanying drawings, Fig. 1 is a 20 central vertical longitudinal section, partly in elevation, of a horizontal type carburetor embodying my invention and showing a vaporizing element positioned therein. Fig. 2, is a central vertical transverse section of said horizontal type carburetor.

25 In a vertical type carburetor, the hydrocarbon fuel feeds considerably above the horizontal line of the air intake and in using a similar vaporizer or pre-heating element in connection with such vertical type, dependence for a flow of the fuel to the vaporizer has been had upon raising a column 30 of fuel through the spray nozzle of the carburetor, by closing the air choke and operating the engine pistons to create a vacuum, then opening the air choke to destroy the 35 vacuum, thus permitting the fuel column to fall back, thereby causing some of the fuel to splash or drain back into an adjacent vaporizer chamber. It is not practicable, however, to use that method with a horizontal 40 type of carburetor; nor has it been wholly satisfactory in connection with a vertical type, especially when the engine is running at high cranking speed, since there is frequently 45 not sufficient drain back or splash to fill the vaporizer chamber, and the heating element sometimes therefore burns out. My present invention provides a positive direct and reliable means and method of automatically 50 filling the vaporizer chamber and prevents

the burning out of the heating element from lack of moisture.

In the drawings, 1 is a carburetor bowl communicating with a carburetor throat 2 through a spray nozzle 3 and through a vaporizer chamber 4. Said spray nozzle is governed by a needle valve 3^a. Said throat is adapted at one end, as at 2^a, to receive air, and is provided at said end with a choke valve 5, to control or stop the admission of 55 said air. The opposite end of said throat is provided with a throttle valve 6, and is provided with a flange 2^c for connecting it to a manifold, not shown.

60 Within said vaporizer chamber is an electric vaporizer 7 of any suitable construction, preferably including an electric resistance wire partly buried in a sponge of asbestos.

Said carburetor bowl contains a float 8 and a needle valve 9 for regulating the flow of 65 hydrocarbon from a main feed pipe 10 to said bowl, as is well known to the art.

70 Connecting said bowl and said vaporizer chamber in any suitable manner, is a connecting pipe 11, to said vaporizer chamber near the upper end thereof but a little below the plane of the upper end of the heating element therein, thus permitting the vaporizer chamber to retain a reserve of fuel received through said pipe which will not drain 75 back through the pipe, and also permitting the heating element to extend above the level of the liquid in the chamber as is desirable 80 in order to effectively vaporize the fuel instead of merely boiling it. It will be observed 85 that when the air choke valve is closed and the engine is turning over, the suction of the piston will effect a very great reduction of atmospheric pressure in the air intake pipe, carburetor throat, chamber 4 and space above 90 the fuel in pipe 11. The fuel will then flow from the carburetor bowl through the fuel spray nozzle of the carburetor into the carburetor throat and manifold. But because 95 of the limitations of the valve-controlled nozzle, the flow therethrough will not be at sufficient speed and in sufficient volume to reduce the atmospheric pressure in the bowl, or compensate the reduction of pressure in 100 the air intake, chamber 4, carburetor throat

and manifold. The continuing pressure in the bowl and the continuing reduction of pressure in the air intake pipe, chamber 4 and space above the fuel in pipe 11 will therefore result in lifting the fuel in pipe 11 to the intake port of chamber 4. Meanwhile the supply in the bowl will be continually replenished through the pipe 10. The amount of flow will depend upon the degree of pressure reduction in the air intake and carbureter throat.

In operation, hydrocarbon of any suitable character, such as gasoline, flows to the carbureter bowl from said pipe 10 under the control of said needle valve and float, as is well known to the art, and rises to an equal level in said connecting pipe 11. When it is desired to start the engine, the air choke valve is first closed and electric current is turned into the heating element or vaporizer. The engine is then cranked in any suitable manner and the suction of the pistons creates a partial vacuum in the carbureter throat and vaporizer chamber, thus drawing fumes from said heater and drawing gasoline from said carbureter bowl up into said vaporizer chamber. If desired the heating element may be energized a few seconds before cranking the engine, and when the engine is then cranked the vaporizer will instantly supply dense clouds of heated fumes available for starting the cold engine. After the engine is started, the air choke valve may be opened, and the electric current may be turned off from the vaporizer, or, if desired the operation of the vaporizer may be continued longer, or intermittently, as occasion may require. The vaporizer chamber is preferably made large enough to contain a considerable supply, or reserve of gasoline to be heated for the cylinders when starting the engine, and to prevent the vaporizer from becoming too dry and burning out.

What I claim is:

1. The combination of a carbureter throat, an air intake conduit communicating with said throat, a fuel reservoir, a choke valve for governing the flow of air through said air conduit, a fuel preheating chamber communicating with said air conduit between said choke valve and said throat, said reservoir being provided with a fuel discharge port adapted to discharge into said preheating chamber at a point above the normal level of fuel in said reservoir only when said choke valve is operated to reduce the flow of air into said air intake conduit.

2. The combination of a carbureter throat, an air intake conduit adapted to discharge into said throat, a fuel reservoir adapted to contain liquid fuel and adapted to discharge into said throat, a source of fuel supply for said reservoir, automatic means for governing the flow of fuel from said source into said reservoir, a valve for governing the flow of

fuel from said reservoir to said throat, a choke valve for governing the flow of air through said conduit, a fuel preheating chamber communicating with said air conduit between said choke valve and said throat, said reservoir being provided with a second fuel discharge port adapted to discharge into said preheating chamber at a point above the normal level of fuel in said bowl and only when said choke valve is operated to reduce the flow of air into said conduit and when a partial vacuum is created in said conduit, and means for heating said chamber.

3. The combination of a carbureter throat, an air intake conduit adapted to discharge into said throat, a choke valve for governing the flow of air into said conduit, a valveless fuel preheating chamber adapted to discharge into said conduit between said choke valve and said throat, a source of fuel supply adapted to discharge into said chamber only when said choke valve is operated to reduce the flow of air into said conduit and only when a partial vacuum is created in said conduit and throat, and means for heating said chamber.

In testimony whereof, I hereunto affix my signature.

IRVING E. ASKE.
